Blower Corporation, a corporation of Pennsyl-
vania

Application May 20, 1936, Serial No. 80,670

10 Claims. (Cl. 257—1)

In Patent No. 1,926,360, granted September 12, 1933, there is disclosed an apparatus for keeping clean the tubes of air preheaters provided with numerous tubes through which the combustion gases from a furnace or furnaces flow. The present invention may be said to have for its object to simplify and improve upon the apparatus of that patent.

In preheaters of the type under consideration, there are vertical tubes arranged in transverse and longitudinal rows; the blowing apparatus comprising a series of transverse blowing elements which are moved step by step, so that each element takes care of a predetermined number of transverse rows of tubes. One of the objects of the present invention is to produce means for moving the actual blower element backward and forward and supplying it with steam or other cleaning fluids that will not only be simpler but shall take up less space than in the construction of the aforesaid patent.

A further object of the present invention is to provide means whereby the blower element may be motor-driven step by step in one direction and be returned in one continuous stroke.

A further object of the present invention is to provide the apparatus with means for automatically reversing its movement at the end of a working stroke and causing it to return to the starting point.

A further object of the present invention is to produce operating means for the blower element which requires only two or three push buttons or the like for fully controlling the same.

A further object of the present invention is to provide means for setting in operation the motor for driving the blower element, and at the same time, opening the valve to admit steam or other cleaning fluid.

In carrying out our invention, we connect to the blower element a rack bar and a pipe for admitting the cleaning fluid, both of which project through the front wall of the casing for the heater, and when the apparatus is idle, lie on the outside of the heater. One of the objects of the present invention is to insure that these two members be cleaned so as to free them of soot or other foreign substances during each cycle of operations of the blowing apparatus.

The various features of novelty whereby our invention is characterized will hereinafter be pointed out with particularity in the claims; but, for a full understanding of our invention and of its objects and advantages, reference may be had to the following detailed description taken in connection with the accompanying drawings, wherein:

Figure 1 is a top plan view of a portion of an air preheater having one of our improved blowing apparatus associated therewith; Fig. 2 is a

section, on a larger scale than Fig. 1, on line 2—2 of Fig. 1; Fig. 3 is a view partly in side elevation and partly in section, of so much of the preheater as is shown in Fig. 1; Fig. 4 is a section on line 4—4 of Fig. 3, but on a larger scale; Fig. 5 is a front view of the preheater; Fig. 6 is a detail illustrating a modified form of control station; and Figs. 7 and 8 are diagrams of connections, showing respectively the control systems corresponding to a control station of the type appearing in Fig. 5 and of the type illustrated in Fig. 6.

Referring to the drawings, 1 represents a shell or casing containing numerous vertical tubes or small flues 2 arranged in two sets of rows at right angles to each other; the transverse rows being comparatively short, and the longitudinal rows being long. It will be understood that the hot gaseous combustion products from a furnace travel upwardly through these tubes or flues, whereas the air to be preheated flows through the shell or casing in contact with the peripheries of the tubes; there being nothing new in this construction which may be said to represent simply an air preheater of the vertical type.

Our improved apparatus for keeping the tubes or flues clean is arranged above the upper flue sheet 3; and, as in the aforesaid patent, it comprises a series of transverse tubular blowing elements 4 provided with nozzles to discharge steam jets into the open ends of the tubes; each blowing element having thereon two rows of nozzles 5 and 6. The blowing elements are connected by longitudinal pipes 7 and 8, by means of which the whole is tied into a rigid hollow or tubular framework. This framework is suspended from transverse axles 9 on the ends of which are suitable wheels 10 running on horizontal rails 11 which extend from front to rear of the preheater. Above the wheels are other rails 12 which keep the wheels from jumping off the rails along which they run.

Steam or other cleaning fluid is supplied to the forward blowing element, which is the righthand element in Fig. 1, through a pipe 14 which is fixed at one end to this blowing element and projects therefrom out through the front wall of the casing of the air preheater. Surrounding the pipe 14 is a larger pipe or tubular housing 15 lying wholly outside of the air preheater casing and preferably supported at one end from the front wall of the latter. The member 15 is somewhat longer than the stroke of the tubular blowing frame and is provided at its rear end with a suitable bearing 13 and at its forward end with a stuffing box 16 which permits the pipe 14 to slide lengthwise while preventing steam from escaping past the pipe. The pipe 14 is provided with openings or windows 17 at such a point that they will always lie within the surrounding housing 60

15 regardless of the position of the blowing device. Steam is admitted into the housing 15 through a supply pipe 18 having therein a valve 19 which may be operated in any suitable manner. Where the entire apparatus is to be automatic, it is advisable that the valve be power operated, and we have therefore shown it as being provided with an electrical operating means indicated conventionally at 20.

10 The tubular blowing frame is adapted to be moved lengthwise by power applied to a long rack bar 21 hinged at one end, as indicated at 22, to the middle of the forward blowing element. This rack bar is slidably mounted in a suitable 15 housing 24 projecting forwardly from a transmission housing 25 mounted on the front wall of the preheater casing. The transmission device has a shaft 26 projecting through the forward wall of the housing and there provided with a 20 belt pulley 27. Suitably supported near the transmission device, in front of the preheater, is a motor 28 on the shaft of which is a belt pulley 29 whose axis is parallel to the axis of the pulley 27. A suitable belt 30 passes around the 25 pulleys 27 and 29 so that, when the motor is in operation, the rack bar is driven lengthwise in one direction or the other, depending upon the direction of rotation of the motor.

When the tubular blower frame is moved toward the back of the preheater casing, the inner ends of the pipe 14 and the rack bar 21 enter the casing and move toward the rear, thereby being exposed to the contents of the casing above the flues. Consequently, more or less soot and other 35 foreign matter will collect on these parts, and we have therefore provided means for cleaning them. In the arrangement shown, as will best be seen in Fig. 4, there is a small pipe 33 arranged on the inner side of the front wall of the pre- 40 heater casing above the rack bar and the steam supply pipe 14. Branches from the pipe 33 are provided with nozzles arranged in pairs 34, 34 and 35, 35; one pair being adapted to blow a cleaning fluid against opposite sides of the pipe 14 45 while the other pair performs the same duty with respect to the rack bar. By admitting cleaning fluid under pressure to the pipe 33 while the blowing unit is making a return stroke, the surfaces of both the pipe 14 and the rack bar are progressively swept clean as they approach near to the front wall of the preheater casing. As can be seen in Fig. 1, the pipe 33 is connected to the main supply pipe through a pipe 36 and a valve 37. This latter valve may be operated in any suitable 50 way as, for example, through an electromagnetic actuator indicated conventionally at 38.

As is usual in apparatuses of this kind, the blowing unit is moved step by step, or inched, from its forward position toward the rear to blow 60 a few transverse rows of flues at a time until all of them are cleaned. It is desirable that the operator in charge be apprised at all times of the position of the blowing unit. This can conveniently be accomplished by placing on the outside 65 of the front wall of the preheater a suitable indicator driven from a moving part of the blowing unit. In the arrangement shown, there is fixed to the front wall of the preheater a long vertical tubular casing 39 in which is located a weight 40; 70 this weight being hung from a cable or other flexible member 41 which passes over suitable guide pulleys 42 and is finally attached to the front end of the rack bar 21. The weight 40 has a finger 44 that projects through a slot 45 that 75 extends throughout substantially the entire

length of the casing or housing 39. Beside the slot are arranged suitable graduations 46, each of which corresponds to a blowing position of the blowing unit. Therefore, as the blowing unit moves back and forth, the finger or pointer 44 indicates the exact position of the unit.

Regardless of whether or not the movements of the blowing unit, after it has once been started, are automatic or semi-automatic, we prefer to provide a limit switch adapted to automatically 10 open the circuit of the motor when the unit reaches its forward position after having completed a blowing operation, and which reverses the motor whenever the unit reaches the rearward limit of its stroke and thereby causes the 15 motor to drive the unit forward again.

The limit switch 47 which appears in Figs. 1, 2 and 5, may be any suitable double-throw switch mounted on the side of the preheater casing in the vicinity of the plane of the tubular blowing unit. The switch shown is of the type having an operating shaft 48 which, in this instance, extends through the wall of the preheater casing, provided at its free end with a radial lever 49 by which it may be actuated. The switch is so mounted that normally the lever extends downwardly and thus lies in the path of movement of a pair of fingers 50 and 51, projecting laterally from the member 3 of the blowing unit. These fingers are spaced apart in the direction from front to rear of the casing a distance equal to the length of a stroke of the blowing unit. When the blowing unit is in its forward position, the finger 50 is engaged with one side of the switch lever or, if it be a snap switch, it will have engaged with one side of the lever until the lever has swung past center; thereby to hold the switch in one of its two positions. The switch remains in that position until the blowing unit has travelled back through a complete stroke, whereupon the finger 51 engages with the switch lever and throws the switch into its other position. When the switch is in this latter position, it causes the motor to be reversed and the blowing unit to start forward on its return stroke.

In the drawings the operating system is one adapted to a three phase motor; power being supplied through three line wires, A, B and C leading into a switch box 53, through which they are connected to automatic control mechanism housed in a casing 54. The whole is manually controlled through suitable push buttons 55 and 56 or the like.

Fig. 7 is a diagram of the electrical system. From this diagram it will be seen that when the switch 57 is closed, the line wires A, B and C are connected directly to the motor terminals D, E and F, respectively, whereas, when the switch 58 is closed, the line wires A, B and C are connected to the terminals E, D and F. Thus, if it be assumed that the switch 57 connects the motor up for forward operation of the motor, whereby the blowing unit is caused to travel from front to rear of the preheater, then the switch 58 may be said to be a reversing switch that will cause the blowing unit to be driven through a return stroke. The switches 57 and 58 are shown as being provided with actuating coils 59 and 60, respectively, by which the switches, normally open, are closed when the coils are energized. Current for energizing the coils 59 and 60 is supplied from the main line through separate circuits controlled by the double-throw limit switch 47. The circuit for the coil 59 includes the push button 55 and a time relay switch 61 of any usual or suitable 70 75 80 85 90 95 100 105 110 115 120 125 130 135 140 145 150 155 160 165 170 175 180 185 construction, whereas the circuit for the coil 60 includes the push button 56. The push button 55 is normally open and the push button 56 is normally closed.

5 Assuming that the blowing unit is at the forward limit of its stroke, as illustrated in Figs. 1 and 3, it will be seen that upon pressing the push button 55, current will flow from line wire A through the coil 59, through the time relay 10 switch, through the push button switch, through the right-hand contacts of the limit switch 47 and back to line wire B. Thus, the coil 59 is energized and the switch 57 is closed, causing the motor to run in the forward direction. As long 15 as the push button 55 is held closed, the motor will continue to run, but intermittently, under the control of the time relay switch. By properly setting this switch, the motor will always run just long enough to move the blowing unit 20 through a single step, namely through a distance equal to the distance between the centers of one transverse row of flues to be blown, and the centers of the flues of the corresponding row in the next adjacent pair of rows; and the motor will 25 then stop long enough to provide an ample jetting time for cleaning the flues over which the nozzles have been brought. When the blowing unit reaches the limit of its rearward movement, the limit switch 47 is automatically thrown into its 30 second working position, namely that in which the left hand contacts in Fig. 7 are engaged with each other while the right-hand contacts are separated. When this occurs, the circuit for the coil 59 is interrupted and the switch 57 is opened. 35 Now, however, the circuit for the actuating coil 60 for the reversing switch 58 is closed; current flowing from line wire A through coil 60, through the closed push button switch 56, through the left hand contacts of the limit switch 47 and back to line wire B. It will be seen that the time 40 relay switch is not included in this circuit, so that the motor runs continuously in the reverse direction and therefore drives the blowing unit back to the starting point in one single movement. When the blowing unit reaches the starting 45 point, namely the position it occupies in Figs. 1 and 3, it automatically throws the limit switch 47 back into the position illustrated in Fig. 7; thereby breaking the circuit for energizing the coil 60 of the reversing switch and making the 50 circuit for the coil 59 ready to be closed again by the push button 55 whenever it is desired to have the blowing apparatus perform another cycle.

Since the main steam valve 19 should be opened 55 at the beginning of a working stroke and be closed during the return movement of the blowing unit, the actuating coil 20 for the valve 19 may be energized whenever the coil 59 is energized. We have therefore connected the coil 20 across the energizing circuit for the coil 59, in parallel with the latter coil. However, one terminal of the coil 20 is connected to the circuit between the push button 55 and the time relay switch, so that the valve will be held open during 60 the time the motor is stopped through the energization of the coil 59 by the time relay switch. Also, since the supply pipe 14 and the rack bar 21 should be cleaned while the unit is making a return stroke, the actuating coil 38 for the valve 65 37 is connected across the energizing circuit for the coil 60 of the reversing switch. Therefore, while the blowing unit is returning to its starting point after the flues have been blown, cleaning fluid will be discharged against the pipe 14 and the rack bar 21, close to the front wall of the

heater casing, so that, as these members move out through the front wall of the casing, their external surfaces are clean.

It will thus be seen that all that the operator need do is to close the switch 55 in order to start 5 cycle operations, and keep it closed until the blowing unit has started back on its return stroke, in order that a cycle may be started and then be automatically completed. He can stop the motor at any time during a working stroke by opening the switch 55 or allowing it to open. Similarly, if it should be desired to stop the unit during a return stroke, he need only open the normally closed emergency switch 56.

If it be desired that the operation of the system be not entirely automatic, any of the automatic features may of course be omitted. In some cases, for example, it may be desirable that the step by step movement of the blowing unit be controlled by the operator rather than by an automatic time relay device. In that case there should be two push buttons or switches corresponding to the push button or switch 55, one for forward movement, and the other for reverse, so as to enable the operator to move the blower unit backward at any time, particularly if he should cause it to make too long a step. The enclosed switch apparatus in this instance would appear as shown in Fig. 6; the switch box 63 taking the place of the box 54 and containing only 15 the main switches 57 and 58, as there is no longer any time relay switch 61. In addition to the push buttons 55 and 56, there is the additional push button 64 which, like the push button 55, 20 comprises a normally open switch.

Fig. 8 is a diagram illustrating this semi-automatic system. In this system, the switches 57 and 58, with their actuating coils 59 and 60, together with the double-throw limit switch 47, are the same as in the automatic system, as is also the circuit for the actuating coil 59 of the switch 57. Paralleling the circuit for the coil 59, however, is a second circuit containing the actuating coil 60 of the reversing switch and the normally open push button switch 64. What may be termed the regular circuit for energizing the actuating coil of the reversing switch, and which contains the emergency switch 56, is the same as in the automatic system. In other words, when the limit switch is in the position shown in Fig. 8, the motor may be caused to run in one direction or the other, depending upon whether the switch 55 or the switch 64 is closed; but, when the limit switch is shifted into its other position, the motor can be driven only in the reverse direction and will run continuously to drive the blowing unit through a complete return stroke unless stopped by opening the emergency switch.

In using the semi-automatic control, assuming the blowing unit to be in the position illustrated in Figs. 1 and 3, the operator presses the push button 55 and holds it down until the pointer on the indicator 39 reaches the first of the graduations 46 on the indicator. At this time the nozzles are properly located over predetermined transverse rows of flues. By taking his finger off the push button, the operator causes the motor to stop. The nozzles thus discharge their jets into the underlying flues until the operator again presses the push button and starts the blowing unit on its way to its next blowing position. In other words, the operator inches the blowing unit through a working stroke. If the indicator shows that the blowing unit has gone a little too far, at any time, the reversing push button may be 75

pressed so as to cause the unit to be retracted and be properly located. At the end of the working stroke, at which time the limit switch is thrown into the position opposite that which it occupies in Fig. 8, the motor circuit is automatically closed in a manner to cause the motor to reverse and drive the blowing unit back to the starting point through a return stroke.

While we have illustrated and described with particularity only a single preferred form of our invention, with a slight modification, we do not desire to be limited to the exact structural details thus illustrated and described; but intend to cover all forms and arrangements which come within the definitions of our invention constituting the appended claims.

We claim:

1. In combination, an air preheater casing or the like, a reciprocable blowing unit in the casing, a cleaning fluid supply pipe fixed to said unit and projecting forwardly through the front wall of the casing, a stationary housing on the outside of the casing surrounding the said pipe and having bearings in which the pipe is slideable, means to introduce cleaning fluid into said housing, and said pipe having an opening in the wall thereof at a point within the housing to admit cleaning fluid thereto, and means to discharge cleaning fluid against the exterior of said pipe in the vicinity of said front wall of the casing.

2. In combination, an air preheater casing or the like, a reciprocable blowing unit in the casing, a cleaning fluid supply pipe fixed to said unit and projecting forwardly through the front wall of the casing, a stationary housing on the outside of the casing surrounding the said pipe and having bearings in which the pipe is slideable, means to introduce cleaning fluid into said housing, and said pipe having an opening in the wall thereof at a point within the housing to admit cleaning fluid thereto, an actuating bar arranged parallel to said pipe hingedly connected at its inner end to said unit and projecting through the front wall of the casing, and means on the outside of the casing to move the actuating bar back and forth.

3. In combination, an air preheater casing, or the like, a reciprocable blowing unit in the casing, a cleaning fluid supply pipe fixed to said unit and projecting forwardly through the front wall of the casing, a stationary housing on the outside of the casing surrounding the said pipe and having bearings in which the pipe is slideable, means to introduce cleaning fluid into said housing, and said pipe having an opening in the wall thereof at a point within the housing to admit cleaning fluid thereto, an actuator connected to said unit and projecting through said front wall of the casing, and means to discharge cleaning fluid against the exterior of the said pipe and the said actuator in the vicinity of said front wall during the movement of said unit toward said wall.

4. In combination, a reciprocable blowing unit, a motor for driving the same, and a control system for said motor to permit said unit to move step by step in one direction and automatically to reverse its movement at a predetermined point in its travel and return to the starting point by a continuous movement.

5. In combination, a reciprocable blowing unit, a motor for driving the same, and a control system for said motor automatically to cause said

unit to move step by step in one direction and automatically to reverse its movement at a predetermined point in its travel and return to the starting point by a continuous movement.

6. In combination, a reciprocable blowing unit, an electric motor for driving the same, switch means to cause the motor to be energized for either forward or reverse rotation, a control system for said switch means including a double-throw switch and one or more manually operable switches, and means on said unit to shift said double-throw switch from one of its positions to the other whenever said unit reaches one or the other limit of its reciprocatory movements. 5

7. In combination, a reciprocable blowing unit, a motor for driving the same, a valve to admit cleaning fluid to said unit, and a control system for said motor and said valve to cause the motor to drive said unit step by step in one direction through a working stroke and automatically to reverse its movement at a predetermined point in its travel and return to the starting point by a continuous movement and to cause said valve to be held open during said working stroke and to be closed during the return stroke. 10

8. In combination, a reciprocable blowing unit, a motor for driving the same, a valve to admit cleaning fluid to said unit, a control system automatically to cause said unit to move step by step in one direction and automatically to reverse its movement at a predetermined point in its travel and return to the starting point by a continuous movement, and means associated with said control system automatically to open and close said valve. 15

9. In combination, a reciprocable blowing unit, an electric motor for driving the same, a valve to admit cleaning fluid to said unit, an electro-magnetic actuator for said valve, switch means to cause the motor to be energized for either forward or reverse rotation, a control system for said switch means including a double-throw switch and one or more manually operable switches, means associated with said system to cause said actuator to be energized and deenergized, and means on said unit to shift said double-throw switch from one of its positions to the other whenever said unit reaches one or the other limit of its reciprocatory movements. 20

10. In combination, an air preheater casing or the like, a reciprocable blowing unit in the casing, a cleaning fluid supply pipe fixed to said unit and projecting forwardly through the front wall of the casing, a stationary housing on the outside of the casing surrounding the said pipe and having bearings in which the pipe is slideable, means including a valve to introduce cleaning fluid into said housing, and said pipe having an opening in the wall thereof at a point within the housing to admit cleaning fluid thereto, an actuator connected to said unit and projecting through said front wall of the casing, a motor for reciprocating said actuator, means including a valve to discharge cleaning fluid against the exterior of the said pipe and the said actuator in the vicinity of said front wall during the movement of said unit toward said wall, and an electro-magnetic control system for said motor and said valves. 25

11. In combination, a reciprocable blowing unit, a motor for driving the same, a valve to admit cleaning fluid to said unit, a control system for said motor and said valve to cause the motor to drive said unit step by step in one direction through a working stroke and automatically to reverse its movement at a predetermined point in its travel and return to the starting point by a continuous movement and to cause said valve to be held open during said working stroke and to be closed during the return stroke, and an electro-magnetic control system for said motor and said valves. 30
